UNITED STATES PATENT OFFICE.

OTTO KRAUS, OF NEW YORK, N. Y.

DESIGN FOR A NECKTIE-FASTENER.

SPECIFICATION forming part of Design No. 34,308, dated April 2, 1901.

Application filed February 8, 1901. Serial No. 46,590. Term of patent 7 years.

To all whom it may concern:

Be it known that I, OTTO KRAUS, a citizen of the United States, residing in the borough of Manhattan, in the city and State of New York, have invented and produced a new and original Design for a Necktie-Fastener, of which the following is a specification.

The subject of the present invention is a new and original design or configuration for a necktie-fastener.

The prominent or conspicuous features of the said design are presented by a plate having a bifurcation longitudinally extending from a medial point therein to one end, the terminal portions of the parallel members formed by the bifurcation being similarly curved with respect to each other, intermediate-located side wings or cheeks integrally extending from the plate and having shoulders and spurs, a bend at the end of the plate opposite to that where the bifurcation terminates, and a tongue depending from the last-mentioned bend, inclining toward the open end of the bifurcation and terminating in a bend.

In the accompanying drawings, forming part of this specification, Figure 1 is a perspective view of a necktie-fastener embodying my new and original design. Fig. 2 is a side view of said fastener, illustrating more particularly the relative position of one of the side wings or cheeks with the bifurcated plate and tongue; and Fig. 3 is a plan view of the fastener.

As shown, the fastener comprises a plate 1,

having the upper contracted part 2 and wider body 3, the latter being bifurcated to present the downwardly-extending parallel members 4 4, the terminals 5 5 of which are similarly curved with respect to each other. The neck 40 2 has a bend 6, from which depends a tongue 7, inclining downward toward the lower open end of the bifurcation and terminating in a bend 8.

Intermediately extending from the edges of 45 the plate 1 are side wings or cheeks 9 9, which are shouldered, as indicated at 10 10, and have prongs 11 11.

By reference to Fig. 2 it will be observed that when the fastener is in such position that 50 the axis of each wing or cheek is horizontal or so that the vertical edges of the shoulders 10 are approximately vertical, to coincide with the dotted line *a a*, the general disposition of the plate 1 will be such that it inclines relative to said axis and vertical line, with its neck 55 and top bend contiguous to the latter.

Having now described my invention, what I claim as new, and desire to secure by Letters Patent, is—

The design for a necktie-fastener, substantially as herein shown and described.

In testimony whereof I have hereunto signed my name in the presence of two subscribing witnesses.

OTTO KRAUS.
